ALBERT C. HERZBERG, OF MEMPHIS, TENNESSEE, ASSIGNOR TO NELLIE M. HERZBERG,
OF NEW YORK, N. Y.

COUPLING DEVICE FOR THE CLOSING-CAPS OF RECEPTACLES AND THE LIKE.

1,200,350.

Specification of Letters Patent.

Patented Oct. 3, 1916.

Application filed December 10, 1915. Serial No. 66,073.

To all whom it may concern:

Be it known that I, ALBERT C. HERZBERG, a citizen of the United States, residing at Memphis, in the county of Shelby and State 5 of Tennessee, have invented certain new and useful Improvements in Coupling Devices for the Closing-Caps of Receptacles and the like; and I do hereby declare the following to be a full, clear, and exact description of 10 the invention, such as will enable others skilled in the art to which it appertains to make and use the same, reference being had to the accompanying drawings, and to characters of reference marked thereon, which 15 form a part of this specification.

The present invention has reference, generally, to improvements in retaining devices for the closing-caps of receptacles, pneumatic-tire valves and the like; and, the invention relates, more particularly, to a novel construction of retaining device adapted to retain in non-separable or connected association with a receptacle, a screw-threaded closing-cap, so that while the latter may be 20 screwed on and off of the neck of the receptacle to close and open the latter, said closing-cap is none-the-less retained in connected or coupled relation with the receptacle so that it cannot be dropped or lost.

The present invention has for its principal object to provide a very simple, cheap and easily applied and operated coupling member or retainer adapted to be associated with the screw-threaded neck of receptacles 30 such as collapsible tubes for paste, paint, toilet preparations, etc., or such as screw-top cans and similar containers, or with the screw-threaded neck of pneumatic-tire valves and such devices, whereby the screw-threaded closing-caps of such articles are 35 coupled or retained in association with the latter to prevent their loss or misplacement when unscrewed from the necks of such articles. Said novel construction of coupling 40 member or retainer being so devised that it freely permits the operation of screwing on and off the said screw-threaded neck of the 45 said closing-cap in the usual manner, yet retaining the said closing-cap in associated or 50 non-separable relation to the receptacle or the like when unscrewed or removed from the screw-threaded neck thereof to open the same.

Other objects of the present invention, not 55 at this time more particularly enumerated, will be clearly understood from the follow-

ing detailed description of the present invention.

With the various objects of my present invention in view, the same consists, primarily, in the novel construction of coupling or retaining device for the closing-caps of receptacles and the like hereinafter set forth; and the invention consists, furthermore, in the novel arrangements and combinations of 60 the various devices and parts, as well as in the details of the construction of the said parts, all of which will be more fully described in the following specification, and then finally embodied in the claims which 65 are appended to and which form an essential part of the said specification.

The invention is clearly illustrated in the accompanying drawings, in which:

Figure 1 is a side elevation of a portion 75 of a receptacle having a screw-threaded neck and a closing-cap associated with the latter, the same being equipped with the novel cap coupling device or retainer, made according to and embodying the principles 80 of my present invention. Fig. 2 is a vertical longitudinal section of the same. Fig. 3 is a horizontal cross section of the same, taken on line 3-3 in said Fig. 2 looking downward. Fig. 4 is another horizontal section 85 of the same, taken on line 4-4 in said Fig. 2, also looking downward. Figs. 5 and 6 are respectively side elevations similar to that shown in Fig. 1, but illustrating respectively, modified forms of construction 90 of the novel cap coupling device or retainer. Fig. 7 is a side elevation of a pneumatic-tire valve to which is applied my novel coupling device or retainer for coupling or non-separably associating therewith its inclosing 95 cap.

Similar characters of reference are employed in all of the hereinafter described views, to indicate corresponding parts.

Referring now to the said drawings, the 100 reference character 1 indicates the main body of a receptacle such as a collapsible tube, to which type of container my invention is peculiarly adapted owing to its construction of wide flexible body and comparatively narrow neck, although I do not wish to be understood as limiting the use 105 or application of my invention to containers or receptacles of such type, since it will be apparent that my invention is capable of 110 use on any kind of receptacle or device having a neck and a closing-cap associated

therewith either by screw-threads or in plain sliding or telescoping relation. Said main body 1 is provided with the usual closing end wall 2 from which rises a neck-portion 3 in which is formed the outlet opening 4 communicating with the interior of the said main body 1. Usually said neck-portion 3 is provided with exterior screw-threads 5 for the reception and engagement of an internally threaded closing-cap 6 adapted to screw thereon to close said outlet opening 4. Located at the base of said neck-portion 3 below the threads 5 thereof, and independent of the thread grooves, is an annular groove or channel 7 extending entirely around the circumference of said neck-portion 3.

One form of my novel coupling device or retainer comprises a ring-like element or base-portion 8, which is adapted to be seated in said groove or channel 7 so as to turn therein circumferentially while yet retained by said groove or channel against vertical movement or rising on said neck-portion 3, thus providing for a swivel-like relation of said coupling device or retainer relative to said neck-portion 3. Connected with said ring-like element or base-portion 8 is an outwardly or radially extending arm 9 from the extremity of which rises an upwardly extending vertical retaining-arm 10, which terminates at its free upper end in a suitably constructed stop-portion 11. Formed upon or secured to said closing-cap 6, preferably adjacent to the lower end of the same, is an outwardly and laterally extending tongue or lug 12 provided with a perforation or opening 13 through which is inserted said retaining-arm 10, so that said closing-cap is slidably related to said retaining-arm 10.

In operating the closing-cap 6 to remove the same from the neck-portion 3, the same is turned circumferentially upon the latter whereby it travels upwardly upon the screw-threads 5. In turning the closing-cap the said retaining-arm 10 rotates around the neck-portion 3 with the closing-cap, this action being permitted by reason of the swivel-like connection of said ring-like element or base-portion 8 in the groove or channel 7 of said neck. Consequently while the closing-cap 6 and retaining-arm 10 rotate together the former rises upon the screw-threads 5, but the latter is free from vertical or rising movement, so that the perforated tongue or lug 12 of the closing-cap 6 moves or slides upwardly upon said retaining-arm 10 until the closing-cap 6 is disengaged from the screw-threads 5 of said neck-portion (as shown by the dotted representation of the closing-cap in Fig. 2 of the drawings). When the said closing-cap is thus freed from the neck-portion 3 it is prevented from being withdrawn or disen-

gaged from the retaining-arm 10 by the stop-portion 11 of the latter, but it may be then turned upon the retaining-arm 10 and dropped down to one side of the neck-portion 3 (as shown by the dotted representation of the closing-cap in Fig. 1 of the drawings), thus removing the same from the outlet opening 4 of the neck-portion, but still retaining the same in coupled or non-separable relation to the receptacle of which it forms the closing member. A reversal of the above described operations will again secure said closing-cap 6 to said neck-portion 3 in closing relation to the receptacle.

Referring now to Fig. 5 of the accompanying drawings, I have illustrated therein a slightly modified construction of my novel coupling-device or retainer, the same comprising a ring-like element or base-portion 14, which is adapted to be seated in said groove or channel 7 so as to turn or swivel therein. Connected with said ring-like element or base-portion 14 is an outwardly extending arm 15 from the extremity of which rises an upwardly extending vertical retaining-arm 16, which is doubled upon itself to provide a downwardly extending portion 17 terminating at its lower end in a loop-end or stop-portion 18. The said closing-cap 6 is provided on its upper surface with a stud-portion 19 around which is anchored or secured one end of a coupling-arm 20, which extends outwardly beyond the periphery of the said closing-cap, and from which extends a downwardly extending arm 21 terminating at its lower extremity, adjacent to the lower end of said closing-cap, in a horizontal ring or eye-portion 22 through which said retaining-arm 16 extends, so that said eye-portion is vertically movable or slidable thereon. The operation of this modified construction of my invention is accomplished substantially in the manner already above described, except that when freed from the neck-portion 3 the eye-portion 22 is moved down upon the portion 17 of the retaining-arm 16 until stopped by the stop-portion 18 (as shown by the dotted representation of the closing-cap in said Fig. 5 of the drawings).

Referring now to Fig. 6 of the accompanying drawings, I have illustrated therein another slightly modified construction of my novel coupling-device or retainer, the same comprising a ring-like element or base-portion 23, which is adapted to be seated in said groove or channel 7 so as to turn or swivel therein. Connected with said ring-like element or base-portion 23 is an outwardly extending arm 24 from the extremity of which rises an upwardly extending vertical retaining-arm 25, which is doubled upon itself to provide a downwardly extending portion 26 terminating at its lower end in a loop-end or stop-portion 27. The said closing-cap 6

is provided adjacent to its upper end with an annular groove 28 in which is seated a ring-like element 29 from which extends downwardly an arm 30 terminating at its 5 lower end, adjacent to the lower end of said closing-cap 6, in a horizontal ring or eye-portion 31 through which said retaining-arm 25 extends, so that said eye-portion is vertically movable or slidable thereon. The operation 10 of this modified construction of my invention is accomplished in the same manner as already described in connection with the previously mentioned constructions.

Referring now to Fig. 7 of the accompanying drawings, I have therein illustrated the application of my novel construction of coupling-device or retainer to a pneumatic-tire valve cap. In this drawing the reference character 32 indicates the valve body which 20 is provided with the usual screw-threaded shank 33 upon which screws the usual cover-cap 34. Located at the base of said shank 33 is an independent annular groove or channel 35 in which is seated so as to turn or 25 swivel therein the ring-like element or base-portion 36 of the coupling device or retainer. Connected with said ring-like element or base-portion 36 is an outwardly extending arm 37 from the extremity of which rises an 30 upwardly extending vertical retaining-arm 38, which is doubled upon itself to provide a downwardly extending portion 39 terminating at its lower end in a stop-portion 40. The said cover-cap is provided, adjacent to 35 its lower end, with a laterally and outwardly extending loop-member or perforated lug 41 through which extends said retaining-arm 38. The operation of the cover-cap and its retainer or coupling device is the same as 40 carried out with the receptacles and closing-caps above described.

It will be clearly understood from the above description that my novel coupling device or retainer may be applied to many 45 articles, and that it provides a device of extreme simplicity, but one easily operated by reason of the swiveling connection thereof to the receptacle or other device to which it is attached. Its construction is not cumbersome, 50 nor of such a design as to impede or interfere with the natural or designed use of the receptacle with which it is connected, and yet it serves very efficiently its function of retaining a closing-cap in coupled 55 or retained relation to the receptacle or the like when the former is removed from closing relation to the latter.

I am aware that some changes may be made in the several arrangements and combinations of the various devices and parts of 60 my present invention, as well as in the details of the construction of the same, without departing from the scope of said invention

as set forth in the foregoing specification, and as shown in the accompanying drawings. 65 Hence, I do not limit my invention to the exact arrangements and combinations of the parts as described in the foregoing specification and as illustrated in the accompanying drawings, nor do I confine myself to the 70 exact details of the construction of the said parts.

I claim:

1. The combination with a receptacle or the like of a screw-threaded neck-portion 75 rising from the main body of said receptacle or the like in such a manner as to provide a substantially horizontally and outwardly extending shoulder at the base of said screw-threaded neck-portion, a screw-threaded closing cap engageable upon said neck-portion, a coupling-device rotatably connected upon said neck-portion but maintained thereon against vertical movement, 80 said coupling-device having an integral vertically and upwardly extending retaining-arm off-set from said neck-portion so as to be spaced away from the latter and said closing-cap, means connected with said closing-cap for slidably associating the same 85 upon said retaining-arm, and a stop-portion connected with the free end of said retaining-arm to prevent displacement of said closing-cap therefrom.

2. The combination with a receptacle or 95 the like of a screw-threaded neck-portion rising from the main body of said receptacle or the like in such a manner as to provide a substantially horizontally and outwardly extending shoulder at the base of 100 said screw-threaded neck-portion, a screw-threaded closing cap engageable upon said neck-portion, said neck-portion having an annular groove located at or adjacent to the juncture of said neck-portion with said 105 shoulder, a ring-like element seated in said groove so as to turn therein and upon said neck-portion with a swivel-like action, a vertically and upwardly extending retaining-arm integrally connected with said ring-like element and off-set to one side of said neck-portion, means connected with said closing-cap providing an opening through 110 which said retaining-arm extends so as to slidably associate said closing-cap with said retaining-arm, and a stop-portion connected with the free end of said retaining-arm to prevent displacement of said closing-cap 115 therefrom.

In testimony that I claim the invention set forth above I have hereunto set my hand this 4th day of December, 1915.

ALBERT C. HERZBERG.
